(57) **CLAIM**

The ornamental design for a reading pillow, as shown and described.

DESCRIPTION

FIG. 1 is a front perspective view of a reading pillow, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective showing the reading pillow, in another state.

All the broken lines in the drawings depict portions of the reading pillow that form no part of the claimed design.
